FLOOR POLISHING UNIT

William C. Harris, Racine, Wis., assignor to S. C.
Johnson & Son, Inc., Racine, Wis.

Application March 11, 1953, Serial No. 23,992

Term of patent 14 years

(Cl. D9—2)

To all whom it may concern:

Be it known that I, William C. Harris, a citizen of the United States, residing at Racine, in the county of Racine and State of Wisconsin, have invented a new, original, and ornamental Design for a Floor Polishing Unit, of which the following is a specification, reference being had to the accompanying drawing, forming part thereof.

Figure 1 is a perspective view of a floor polishing unit showing my new design.

Figure 2 is a top plan view of the floor polishing unit shown in Figure 1.

Figure 3 is a side elevational view of the floor polishing unit shown in Figure 1.

Figure 4 is a back elevational view of the floor polishing unit shown in Figure 1.

Figure 5 is a front elevational view of the floor polishing unit shown in Figure 1.

The side not shown is substantially the same as the one shown in Figure 3.

I claim:

The ornamental design for a floor polishing unit, as shown and described.

WILLIAM C. HARRIS.
